(57) **CLAIM**

The ornamental design for a putter head, as shown and described.

DESCRIPTION

FIG. 1 is a top view of the putter head, showing my new design.

FIG. 2 is a front view of the putter head.

FIG. 3 is a heel view of the putter head; and,

FIG. 4 is a bottom view of the putter head.

The broken line showing a hole for a shaft and weighting on the bottom of the putter head is for illustrative purposes only and forms no part of the claimed invention.
